UNITED STATES PATENT OFFICE.

EUGENE HOY, OF MEMPHIS, TENNESSEE.

EXCAVATOR.

No. 923,528.

Specification of Letters Patent.

Patented June 1, 1909.

Application filed December 10, 1908. Serial No. 466,795.

To all whom it may concern:

Be it known that I, EUGENE HOY, a citizen of the United States, residing at Memphis, in the county of Shelby and State of Tennessee, have invented certain new and useful Improvements in Excavators, of which the following is a specification.

This invention relates to apparatus for excavating and dredging, and has particular reference to apparatus employed in the construction and maintenance of levees.

The invention includes several specific details of construction to be hereinafter described and claimed and illustrated in the accompanying drawings, in which—

Figure 1 is a diagrammatic plan indicating in a general way an apparatus comprising this invention; Fig. 2 is a perspective view of a conventional form of wheeled scoop, 20 with my invention applied thereto, certain parts being broken away to disclose that which would otherwise be hidden; Fig. 3 is a perspective view of a portion of the mechanism of Fig. 2, viewed from a different direction; Fig. 4 is a perspective view of a corner detail, indicating the means for directing the carrying mechanism around the turn; Fig. 5 is a detail of the corner sheave and its support; Fig. 6 is a side view of the clutch, indicating its position when applied to the power rope, and Fig. 7 is a plan view of the same.

Throughout the following detail description and on the several figures of the drawings similar parts are referred to by like reference characters.

The apparatus comprising this present invention includes certain novel features of construction in connection with an endless 40 flexible cable 10, driven in any suitable manner by means of a relatively stationary power plant including frictional driving mechanism 11, which receives its power from any suitable source, such as an engine 12 receiving its 45 fluid from a boiler 13. The cable 10 may be of any suitable nature and of any desired length, depending upon the work to be done and the conditions to be met.

As indicated in Fig. 1, the apparatus is intended for operation over a considerable extent of territory,—say to the extent of two hundred or more feet in width and three hundred or more in length. In the construction of levees it is desirable and some times obligatory that large masses of earth be moved and placed in a comparatively short time,

and to this end I contemplate employing a large number of wheeled scoops, such as are commonly drawn by mules or horses, and connect the same detachably to the endless 60 cable 10, whereby the scoops will be drawn, the cable being operated continually at any desired rate of speed. That portion of Fig. 1 indicated at A may be understood to represent the location of the levee to be constructed and the territory represented by B as that from which the earth is taken to construct the levee.

In Figs. 2 and 3 I have indicated a wheeled scoop 14 having applied thereto certain novel 70 features of construction whereby the same is adapted especially for use in my apparatus. Such structure includes a frame 15 of generally rectangular outline. The frame 15 includes a pair of substantially parallel side 75 bars 16, which are curved or extended downwardly at their rear ends at 16' and terminate in an attachment means 17, shown in the form of eyes, whereby the same may be connected in any suitable manner to the wheeled 80 scoop, herein indicated as being attached to the hounds where ordinarily the draft tongue would be connected when the scoop is being drawn by draft animals. A pair of hooks 85 are connected at their forward ends to the frame 15 and have detachable connection at their rear or hooked ends 19 to the scoop, the said hooks being adapted for disengagement from the scoop during certain operations thereof. Wheeled scoops of the character 90 referred to are usually provided with an arched axle 20 from which the scoop is suspended by means of hangers 21, the said arched axle being tilted at certain times 95 during the loading and unloading of the scoop. In order to prevent an accidental forward tilting of the axle, which might occur in case the point of the scoop should engage a slight obstruction, I provide a locking means 100 in the form of a bar 22 pivoted at 23 on the frame 15. The forward end of the bar 22 is provided with a foot piece 22', whereby the operator seated upon the seat 24 may by depression of his foot against the tension of a leaf spring 22^a lift the rear end of the bar 22 105 out of alignment with the upper portion of the axle 20 and permitting of the dumping of the scoop in the usual manner. At the forward end of the frame 15 is mounted a supporting and steering wheel 25, to the upper end of whose fork 26 is connected a steering lever 27, having interlocking engagement 110

with a toothed segment 28 rigidly connected to the frame, the rear end of the lever being provided with a handle 29 within reach of the operator. By means of the steering mechanism described the operator may cause the wheeled scoop to partake of a wide range of movements for the purpose of being loaded and depositing the soil carried thereby, and also whereby he may by locking the mechanism insure that the wheeled structure will partake of operation in substantially a right line.

In order to attach my wheeled scoop to the power cable 10 I employ a suitable form of detachable clutch 30, comprising a main jaw 31 and a jaw 32 pivotally connected thereto. The jaw 31 is provided with a double curved or ogee shaped gripping end for immediate connection with the cable and at its other end with a shank 31'. The said jaw is provided with an intermediate slot 33 within which is mounted the jaw 32 on a pivot 34. The gripping end 35 of the jaw 31 is provided with a cable seat, the said seat being on the outside of the jaw and disposed at an oblique angle to the jaw. The jaw 32 is provided with an outer curved end which substantially conforms to one portion of the curvature of the jaw 31 and whose extreme outer end 36 is adapted to substantially embrace the cable seated in the cable seat to prevent displacement thereof in one position of the jaw 32. The opposite or inner end of the jaw 32 is provided with a shank 32', which lies against or close to the under side of the shank 31' of the other jaw. The said shanks are provided with eyes 37 which substantially register with each other and through which is passed a rope or cable 38 formed into a loose loop which will permit the shanks 31' and 32' to be readily separated by the hand of the operator when it is desired to separate the gripping portions of the jaws to detach the clutch from the cable. The inner end of the rope is attached to a ring 39 detachably connected to the frame 15 of the scoop structure. As a preferred means for connecting said ring 39 to the frame I provide a catch 40 provided with an intermediate curved seat for the ring and pivoted at one end on a stationary pivot 41 between a bracket 42 and one bar 16 of the frame. After receiving the ring 39 in the curved seat the catch is turned upwardly and rearwardly and the free end 40' of the same is locked by a lever 43 holding the catch in a position to prevent displacement of the ring 39 therefrom. Said lever 43 is pivoted at the rear end of the bracket 42 and has a downwardly projecting extension 43' to which a coiled spring 44 is connected, the other end of the spring being connected to the frame and whereby the normal tendency of the spring is to hold a shoulder 45 of the lever in contact with the free end of the catch 40. Upon rearward

movement of the lever 43 the operator sets the catch free for the purpose of permitting automatic detachment of the power rope 38 therefrom, as for instance when the wheeled scoop has reached the place where it is to be filled by any suitable means.

In order for the power rope 38 to maintain its connection with the power cable 10 while passing around the turns there is employed preferably at each turn or corner a direction sheave 46 keyed to the upper end of a stud 47 mounted in a bearing 48, the bearing being supported by a portable truck 49. The truck and parts sustained thereby will be anchored in any suitable manner as indicated at 50. As will be seen from the description of the clutch 30, the same is adapted for coöperation with the sheave 46, maintaining connection with the power cable 10 while passing therearound. The inner surface of the lower ~~curved~~ portion of the jaw 31 conforms to the groove of the sheave 46, and the shank portion of the scoop 30 will be directed over the upper face of the sheave so as to prevent undesirable contact between the shanks of the scoop and the edge of the sheave. For this purpose I employ a guard rail 51 secured as indicated in Figs. 1 and 4 to the frame of the sheave support in such a manner as to extend at one end 51' beneath the cable 10 and at the other end 51" above the cable and sheave. The location of the guard rail 51 is such that its main portion, viewed in plan, is parallel to the cable and within the run of the same.

As viewed in Fig. 1 a scoop will be drawn from the region B in the direction of the arrow a to and upon the levee A and whereupon at any desired point the scoop will be dumped in the usual manner. The scoop, however, will be maintained in connection with the power cable 10 until it approaches the power plant 11. At this point the scoop will have reached an inclined runway 52 and down which it will gravitate, the steering apparatus being properly set for this purpose. The operator of the scoop, or some other party, will then detach the clutch 30 from the power cable 10 and promptly pass around the power station 11 and subsequently attach the clutch again to the cable on the opposite side of the power station in order that the wheeled scoop may continue on its course toward the region where it will be again filled for a succeeding operation. As many wheeled scoops may be employed in connection with my apparatus as may be accommodated by the power cable. By attaching the power rope 38 at one side of the frame 15 the side draft on the wheeled structure will assist the steering mechanism in maintaining the path for the scoop to a considerable distance inwardly from the line of the power cable 10. By this fact and also the dirigibility of the wheeled structure it is possible

to operate the scoops over a wide extent of territory. I prefer to employ in connection with the frame 15 braking mechanism for the wheels 53 of the scoop. Said mechanism includes a pair of shoes 54 mounted on independently journaled shafts 55, to the cranks of which draft rods 56 are connected at one end and whose other ends are connected to upwardly extending arms 57 of a crank 58 operated by a brake lever 59 within reach of the operator.

Having thus described the invention, what is claimed as new, is—

1. In an apparatus of the character described, the combination with an endless power cable, of one or more wheeled scoops, a power rope connected to each wheeled scoop and detachably connected to the power cable, a series of guide sheaves directing the power cable around the turns, and means associated with each sheave to cause the power rope to pass freely over the top of the sheave.

2. In an apparatus of the character set forth, the combination with an endless power cable and means for operating the same continually, of one or more wheeled scoops operable within the runs of the said power cable, a power rope connected at one end to each scoop and at the other end detachably connected to said power cable, a horizontally disposed guide sheave at each turn of the cable, and a guide rail associated with the said sheave and having one end beneath the cable and the other end above the sheave to cause the power rope to pass freely over the sheave while attached to the power cable.

3. In an apparatus of the class described,

the combination with an endless power cable and means for driving the same continually, of a wheeled scoop embodying a frame connected at one end to the scoop structure, steering devices supporting the front end of the frame, a power rope connected to the power cable and detachably connected at one side of said frame, for the purpose set forth.

4. In an apparatus of the character set forth, the combination with an endless power cable and means for driving the same continually, of a wheeled scoop comprising a frame connected at its rear end to the scoop structure, steering devices including a wheel connected with the other end of the frame, a power rope connected to said endless cable, and means for detachably connecting said rope to the frame, said means including a pivoted catch, and a spring operated lever to prevent movement of the catch on its pivot.

5. The herein-described wheeled scoop embracing an upwardly arched axle, a scoop suspended from the axle, a frame connected to the scoop structure, means to support and steer the other end of the frame, means to propel the aforesaid devices, and means to prevent unauthorized tilting of the said axle, said means comprising a lever pivoted on the frame and adapted to abut at one end against the said axle when in normal position.

In testimony whereof I affix my signature in presence of two witnesses.

EUGENE HOY
